UNITED STATES PATENT OFFICE.

LIDA KINGSLEY WALKER, OF ST. CATHARINES, ONTARIO, CANADA.

DESIGN FOR A DOLL.

Application filed January 15, 1925. Serial No. 12,061. Term of patent 3½ years.

To all whom it may concern:

Be it known that I, LIDA KINGSLEY WALKER, a subject of the King of Great Britain, and resident of the city of St. Catharines, county of Lincoln, Province of Ontario, in the Dominion of Canada, have invented a new, original, and ornamental Design for a Doll, of which the following is a specification, reference being had to the accompanying drawing, forming part thereof.

The figure is a front view of a fabric doll showing my new design, the shoe being left off of one foot.

I claim:

The ornamental design for a doll as shown.

LIDA KINGSLEY WALKER.
